UNITED STATES PATENT OFFICE.

JAMES M. SPANGLER, OF CANTON, OHIO, ASSIGNOR TO THE HOOVER SUCTION SWEeper COMPANY, OF NEW BERLIN, OHIO, A CORPORATION OF OHIO.

DETACHABLE BRUSH-GUARD FOR CARPET-SWEEPERS.

974,304.

Specification of Letters Patent.

Patented Nov. 1, 1910.

Application filed August 11, 1910. Serial No. 576,686.

To all whom it may concern:

Be it known that I, JAMES M. SPANGLER, a citizen of the United States, residing at Canton, in the county of Stark and State of Ohio, have invented a new and useful Detachable Brush-Guard for Carpet-Sweepers, of which the following is a specification.

My invention relates to attachments for carpet sweepers and consists of a guard for the brush of said sweepers, said guard being readily detachable from the sweeper and being adapted, when applied, to prevent carpets, rugs, the corners and edges of rugs and other floor coverings from being drawn up too far into the brush mechanism and to perform other useful functions as will hereinafter more fully appear.

The invention is especially applicable to that class of carpet sweepers wherein air is drawn into the sweeper adjacent the brush for the purpose of lifting the dust and dirt and more thoroughly cleaning the rug. There are at present a number of practical applications of this combination of brushing and pneumatic cleaning, an example of such construction being shown in applicant's United States Patent No. 889,823, issued June 2, 1908.

In the more successful carpet sweepers employing both brushing and pneumatic cleaning means it has been found desirable to provide means for causing an inrush of air of considerable force. With a forceful inrush of this kind considerable annoyance has been given by reason of the fact that the corners and edges of rugs and other floor coverings are frequently drawn up within the carpet sweeper and into engagement with the brushing and other mechanism therein contained, thus both injuring the carpet sweeper and its mechanism and also doing more or less damage to the floor coverings. Moreover when portions of the floor covering are thus drawn within the sweeper the said sweeper cannot properly perform its work and it therefore becomes essential to successful operation of the device that some means be provided for preventing said floor coverings from being drawn within the sweeper and for holding said coverings in proper position for the sweeper to do thorough sweeping and cleaning.

The objects of my invention are to generally increase the effectiveness of carpet sweepers by providing a suitable attachment

of the character described and to provide a detachable brush guard which will be simple in construction, cheaply manufactured, readily connected or detached from the sweeper, and fully capable of thoroughly accomplishing its purpose. These objects, together with other objects readily apparent to those skilled in the art, I attain by the construction illustrated in the accompanying drawings, although my invention may be embodied in other forms, the construction illustrated being chosen by way of example.

In the drawings Figure 1 is a perspective view of an inverted brushing-pneumatic carpet sweeper provided with a detachable brush guard embodying my invention. Fig. 2 is a perspective view of the brush guard showing certain adjustments of parts by dotted lines. Fig. 3 is a fragmentary sectional view upon a vertical plane showing the brushing portion of such a carpet sweeper as illustrated in Fig. 1, a brush guard of my invention being included and the sweeper in operative position upon a carpeted floor.

Throughout the several views similar reference numerals indicate similar parts.

The numeral 1 indicates the upper or top portion of the carpet sweeper casing and the numeral 2 the handle yoke to which the handle is connected. The sweeper is provided with a bottom 3 and with an air and dust discharge pipe 4. An electrically operated fan or other air drawing means is arranged within the casing 1, said means being adapted to forcibly draw air in through the brush opening 5 in the bottom 3 and discharge the same through the pipe 4 into a dust receiving means.

The details of construction of the parts just named is not claimed herein and need not be more fully described.

The sweeper is mounted upon suitable wheels 6 and casters 7 adapted to permit the sweeper to be easily moved about upon the floor and also adapted to hold the bottom 3 in spaced relation to said floor. Within the casing at the brush opening 5 is a rotatable brush 8 having its axis horizontally disposed, the bristles of said brush protruding through the opening 5 a sufficient distance to extend an eighth of an inch, more or less, below the general plane of the bottom 3. Suitable driving means for the brush is provided, as for instance the belt 9 which is op-

eratively connected with the mechanism on the inside of the sweeper casing and adapted to produce rotation of the brush when said mechanism is operated.

In Fig. 3 it will be noted that the bottom 3 of the sweeper is spaced from the surface of the floor 10 and that the bristles of the brush 8 extend below the bottom 3 as just described, but not sufficiently far to contact 10 with the floor 10. In Fig. 3 a rug or other floor covering 11 is illustrated, the portion of said covering immediately below the opening 5 being shown as drawn up across said opening and against the edges thereof 15 by the forceful inrush of air, or as it is commonly expressed, by the "suction". In this position the revolving brush contacts with the floor covering, said contact constituting both a brushing and a rapid tapping and 20 shaking of that portion of the covering held across the opening 5 as described.

From the foregoing the importance of a brush guard will be readily apparent and as it sometimes becomes necessary to remove 25 the brush through the opening 5 or to clean the same and free it from threads and the like it is desirable that said guard be readily detachable.

Referring now more particularly to the 30 brush opening and guard it will be noted in the drawings that the wheels 6 are mounted in wheel casings 12, the forward ends 13 of which extend inwardly a short distance from the ends of the opening 5 slightly back of the rear edge thereof. It will also be noted that the casing 1 in that portion over the brush is curved as at 14 from the horizontal portion 15 to the front vertical portion 16. The horizontal, inwardly turned flange 17 35 extends from side to side of the sweeper along the front edge of the opening 5, said flange providing a ledge upon the interior of the casing.

The brush guard proper consists of a base 45 bar 18 adapted to extend from end to end of the opening 5 upon the inside thereof, resting upon the ledge formed by the flange 17. At each end of the bar 18 the curved retaining arms 19 are provided, which arms 50 are formed of spring material and are rigidly fastened to the bar 18. The curvature of the arms 19 is such as to substantially conform to the curvature of the parts 16, 14, 15, the free ends of the arms, however, having less curvature, the said arms being adapted to engage the inner side of the portion 15 and the ends of said arms adapted to engage the forward ends 13 of the wheel casings.

60 Rigidly connected to the bar 18 on the opposite side thereof from the arms 19 are the guard fingers 20 which are formed of spring material and extend backward from the bar 18 and at substantially right angles 65 thereto.

The method of attachment will be readily understood from an inspection of Fig. 3 where it will be seen that the ends of the arms 19 and fingers 20 are introduced into the opening 5 and sprung toward each other 70 a sufficient distance to permit the device to enter. The ends of the arms 19, upon striking the curved portion 14, will be directed backward along the portion 15 until the ends of the arms engage the front ends 13 75 of the wheel casings. It is then necessary to forcibly push inwardly and forwardly upon the bar 18, springing the middle portions of the arms 19 outwardly and nearer to the portions 14 and 16 until the bar 18 80 can be seated upon the ledge formed by the flange 17. As the fingers 20 extend from the under side of the bar 18 it is necessary to provide notches in the flange 17, as illustrated in dotted lines at 21, to receive the curved portions 22 of the fingers 20. In Fig. 3 it will be noted that when the guard is in place in the sweeper the ends of the fingers 20 bear upon the inner side of the bottom 3 along the rear edge of the opening 5 and being under tension by reason of having been sprung closer than normally to the arms 19, said fingers will assist in producing spring contact of the arms 19 against the portion 15 of the casing, thus serving 95 to keep the bar 18 firmly in place and prevent the loosening of the guard. For the purpose of holding the bar 18 well forward upon the flange 17 and in engagement with the portion 16 the fingers 20 are upwardly 100 bent near their free ends, the downward pressure of said free ends along the rear edge of the opening 5 thus producing a forward thrust of said fingers sufficient to maintain the bar 18 in proper position. In 105 addition to thus holding the guard in proper position the bent free ends of the fingers 20 permit the main portion of said fingers between said bent portion and the bar 18 to lie in the same plane as the bottom 3, the lower sides of said fingers across the opening being in a plane with the bottom surface of the said bottom 3.

When it is desired to remove the guard it is only necessary to grasp the fingers 20 in 115 the hand, press upwardly thereon and backwardly, thus unseating the bar 18 from the flange 17, whereupon said bar may be drawn out of the opening 5 adjacent the front edge thereof, the arms 19 and fingers 20 being 120 sprung sufficiently to permit the guard to be withdrawn by reversing the operation by which it was inserted.

I claim:—

1. For carpet sweepers of the character 125 described, a brush guard comprising the base bar 18, the curved spring arms 19 rigidly connected to said base bar and the spring fingers 20 rigidly connected to said base bar on the opposite side thereof from 130

the arms 19 and extending at right angles from the bar 18, substantially as described.

2. For carpet sweepers of the character described, a brush guard comprising a base bar, spring arms rigidly connected to said base bar, and a plurality of spring fingers rigidly connected to said base bar opposite said arms.

3. A device of the character described comprising a base bar, curved retaining arms formed of spring material and rigidly fastened to said bar and a plurality of guard fingers formed of spring material, rigidly connected to said bar and extending outwardly from said bar at substantially right angles thereto and opposite said arms, the free ends of said arms and fingers adapted to be temporarily sprung out of their normal position into positions to bring said arms and fingers nearer to each other.

4. A detachable brush guard for carpet sweepers provided with a casing and bottom, a brush opening in the bottom, a brush mounted upon a horizontal axis within said casing and having its bristles protruding through said brush opening and an interior

ledge along one edge of said brush opening, said brush guard comprising a base bar, spring arms rigidly connected to said base bar, a plurality of spring guard fingers rigidly connected to said base bar and extending at right angles thereto and in line with the direction of rotation of said brush, said arms and fingers adapted to be sprung toward each other to permit said guard to be inserted through said brush opening, said base bar adapted to rest upon said internal ledge, said arms adapted to bear against said casing to hold said base bar in place upon said ledge and said guard fingers adapted to extend across said brush opening, the bottom sides of said fingers lying in substantially the same plane with the lower surface of the bottom of said sweeper.

In testimony that I claim the above, I have hereunto subscribed my name in the presence of two witnesses.

JAMES M. SPANGLER.
